UNITED STATES PATENT OFFICE.

MURRAY CUTHBERT TUNISON, OF LOS ANGELES, CALIFORNIA.

DESIGN FOR AN AUTOMOBILE ROADSTER BODY.

Application filed June 9, 1924. Serial No. 9,831. Term of patent 3½ years.

To all whom it may concern:

Be it known that I, MURRAY CUTHBERT TUNISON, a citizen of the United States, residing at Los Angeles, in the county of Los Angeles and State of California, have invented a new, original, and ornamental Design for an Automobile Roadster Body, of which the following is a specification, reference being had to the accompanying drawing, forming a part thereof.

Figure 1 is a side elevation of a roadster body embodying my design.

Fig. 2 is a fragmental perspective show-

ing the rear end of the roadster body shown in Fig. 1.

I regard the automobile top portion of the present body design as the salient feature thereof.

I claim:

The ornamental design for an automobile roadster body, as shown.

Signed at Los Angeles, in the county of Los Angeles, and State of California, this 27th day of May, 1924.

MURRAY CUTHBERT TUNISON.
